DOLLY FOR RETREADING MOLDS AND OTHER
WHEEL-LIKE ARTICLES

Rudolph E. Olson, Minneapolis, Minn., assignor to Paul
E. Hawkinson Company, Minneapolis, Minn., a corpo-
ration of Minnesota

Filed Oct. 26, 1964, Ser. No. 82,317

Term of patent 14 years

(Cl. D14—3)

FIG. 1

FIG. 2

FIG. 1 is a view in perspective of a dolly for retreading molds and the like, showing my new design; and

FIG. 2 is a view in perspective thereof as seen from the side opposite to that shown in FIG. 1.

I claim:

The ornamental design for a dolly for retreading molds and other wheel-like articles, as shown.
